UNITED STATES PATENT OFFICE.

ARTHUR D. TEEPELL, OF LOS ANGELES, CALIFORNIA.

CONVERTIBLE PLANE.

Application filed May 5, 1924. Serial No. 711,167.

To all whom it may concern:

Be it known that I, ARTHUR D. TEEPELL, a citizen of the United States, residing at Los Angeles, in the county of Los Angeles and State of California, have invented new and useful Improvements in Convertible Planes, of which the following is a specification.

This invention relates to hand planes and 10 consists of the novel features herein shown, described and claimed.

An object is to make a hand plane having a central plane element and having extension members which may be readily applied 15 to either or both ends of the central element.

Another object is to combine with a plane, one or two extension members which may be optionally connected to one or both ends of the plane.

20 Other objects and advantages will appear from the drawings and specification.

The drawings illustrate a plane embodying the principles of my invention.

Figure 1 is a top plan view of a plane 25 embodying the principles of my invention, the view being taken looking in the direction indicated by the arrow 1 in Fig. 2.

Fig. 2 is a side elevation as indicated by the arrow 2 in Fig. 1, parts being broken 30 away and shown in section.

Fig. 3 is a vertical cross section on the lines 3—3 of Figs. 1, 2 and 4, and looking in the direction indicated by the arrows.

Fig. 4 is a fragmentary vertical longitudinal section on the lines 4—4 of Figs. 1 35 and 3.

Fig. 5 is a top plan view of one of the extension members shown in Figs. 1 and 2.

Fig. 6 is a vertical longitudinal sectional 40 detail on the line 6—6 of Fig. 5, and looking in the direction indicated by the arrows.

The details of the plane embodying the principles of my invention as shown in the drawings are as follows:

45 The central plane element 1 may be of any ordinary construction so far as the planing features are concerned and so far as it is to be used as a short plane. In carrying out my invention an extension member 2 is removably applied to each end of the plane element 1 so that the plane element 1 may be lengthened at either or both ends, or may be used without lengthening.

50 The plate 3 of the plane element 1 having the bearing face 4 for engaging the

work also has a flat upper face 5. A central internally screw threaded and externally finished lug 6 extends upwardly from the face 5. Ledges 7 and 8 extend inwardly from the upper parts of the sides 9 and 10, said sides 9 and 10 extending upwardly from the side edges of the plate 3 and the lower faces 11 of the ledges 7 and 8 are slightly tapered or inclined from the outer ends 12 inwardly and downwardly, thus 65 making wedge shaped seats 13 and 14.

The extension member 2 has a flat plate 15 adapted to align with the plate 3 and has sides 16 and 17 adapted to align with the sides 9 and 10. A shank 18 has a plate 19 offset upwardly relative to the plate 15 and fits upon the face 5. A tapered central opening 20 is formed at the center of the plate 19 and a slot 21 extends from the inner end of the plate 19 to the opening 20 so that 70 the lug 6 will pass through the slot 21. The plate 19 has sides 22 and 23 offset relative to the sides 16 and 17 so as to fit between the sides 9 and 10, and the sides 22 and 23 have upper inclined faces 24 and 25 to fit 75 the lower faces 11 of the ledges 7 and 8 like wedges.

The handle 26 is mounted upon a shank 27 and held in place by a screw 28, and a stud bolt 29 is mounted in the shank 27 to screw into the lug 6. A cone 30 is formed upon the lower end of the shank 27 concentric to the stud 29, and has an inner recess to receive the lug 6 and an outer tapered face 31 to engage in the tapered opening 20 90 so that when the handle 26 is manipulated to screw the cone 30 down the tapered face 31 of the cone engaging the tapered opening 20 will draw the wedges 22 and 23 firmly into the seats 13 and 14 and hold the extension 2 tight and rigid upon the element 1.

While I have shown in detail and described the right hand extension member 2 in Figs. 1 and 2, it is to be understood 100 that the left hand extension member 2 is constructed and applied in the same way. The handle 26 serves in operating the main plane element 1 when the extension members are disconnected, and the extension members 105 are readily applied by manipulating either handle.

Thus I have produced a plane having a central plane element which is complete in itself to be used as a short plane, and hav- 110

ing extension elements which may be applied to either or both ends of the central plane element as desired.

Various changes may be made without departing from the spirit of the invention as claimed.

I claim:

- 10 1. A plane having seats and a centering lug, an extension member fitting the seats and having a centering opening, a cone fitting the centering lug and centering opening, a handle upon the cone, and a stud bolt carried by the handle to screw into the centering lug to clamp the parts together.
- 15 2. A plane having seats and a centering lug, an extension member fitting the seats

and having a centering slot leading to a centering opening, a cone fitting the centering lug and centering opening, a handle upon 20 the cone, and means for connecting the handle to the centering lug to clamp the parts together.

3. A plane having tapered seats and a centering lug, an extension member having tapered sides to fit the seats and having a centering slot leading to a centering opening, a cone fitting the centering lug and centering opening, a handle upon the cone, and a bolt 25 for connecting the handle to the centering lug to clamp the parts together.

In testimony whereof I have signed my name to this specification.

A. D. TEEPELL.
